UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

PLANING-MACHINE.

1,032,806.

Specification of Letters Patent. Patented July 16, 1912.

Application filed July 3, 1908. Serial No. 441,865.

To all whom it may concern:

Be it known that I, ARTHUR BATES, a subject of the King of Great Britain, residing at Leicester, in the county of Leicestershire, England, have invented certain new Improvements in Planing-Machines, of which the following description, in connection with the accompanying drawings, is a specification, like reference characters on the drawings indicating like parts in the several figures.

This invention relates to an improvement intended for presses and more especially presses in which one of the pressure members is made of wood or similar material which is liable to become roughened or uneven under repetition of the pressing operation, and comprises an attachment to presses of the above type by which such inequalities or roughness of the pressure member may be removed and a smooth surface imparted thereto.

This invention is especially applicable to that class of presses of the above type that are used for dying out sheet material, such as leather, felt, etc. Presses of this type usually have a wood cutting bed into which the sharp edge of the die is forced slightly in the operation of the machine. It will be readily understood that such a bed soon becomes roughened under this action of the die and must be re-surfaced. Especially is this the case when the member which acts to force the die toward the bed has a movement substantially parallel to the surface of the bed in addition to its pressure applying movement which is substantially perpendicular to such bed, as a member having these two movements will sometimes act to force the die toward and into the bed with a combination of these two movements, thus greatly shortening the time within which the surface of the bed becomes too rough for satisfactory work.

The device of this invention is also useful when the surfaces of the pressure members are not exactly parallel whether this is due to irregularity in the mounting of one or both of said members or to other reasons, and in such cases may be employed to bring the said surfaces into the desired parallel relationship.

Hitherto it has been the custom to remove the bed from the machine when its surface

has become roughened or when for other reasons it has become desirable to impart a new surface thereto. After the removal of the bed from the machine its surface was removed to a uniform depth by a plane operated by hand or power. In cases of irregularity in the mounting of one or both of the pressure members on the machine and in cases, therefore, in which the said bed and its coöperating pressure member are not supported in exact parallelism, the above method is incapable of imparting a surface to the bed which shall be exactly parallel with the surface of the other pressure member, owing to the necessity in such cases of removing the different portions of the surface of the bed to different depths.

A principal feature of this invention relates to an attachment to be applied to presses of the above or similar types by means of which the surface of the bed may be trued into parallelism with the acting face of the coöperating pressure member.

Another feature of this invention relates to a resurfacing attachment to be applied to presses of the above or similar types in which the movement of the pressure applying member relatively to the bed may be utilized to operate the means for re-surfacing the bed and for imparting thereto a surface parallel to the movement of the said pressure applying member.

A further feature relates to means for causing the re-surfacing means to act on different portions of the bed on successive actuations of the said pressure applying member, while another feature relates to the provision of means for reversing the movement, relatively to the bed, of the re-surfacing means, and still another feature of the invention relates to the provision of means for preventing actuation of the pressure members relatively to each other while the truing or smoothing tool is in position between them.

Further features of the invention relate to the provision of means for adjusting the feeding means for the tool as the bed is worn or smoothed down, and for preventing injury to the feeding means should the feeding means become stuck for any reason.

Referring to the accompanying drawings which show a preferred embodiment of this invention, Figure 1 is a side elevation, partly

broken away, of a press having the present invention applied thereto; Fig. 2 is a vertical section on the line 2-2, Fig. 1; Fig. 3 is an end view of the attachment looking in the direction of the arrow *a*, Fig. 1, 5 and showing the feeding mechanism; Fig. 4 is an end view looking in the direction of the arrow *b*, Fig. 1; Fig. 5 is an end view, partly broken away, showing a slightly modified form of feeding mechanism; and 10 Figs. 6 and 7 are details showing respectively one end of the knife and a part of the means for preventing vertical actuation of the swinging arm when the attachment is in place.

15 The frame of the machine is indicated at 2 and as shown supports the presser bed 4, preferably of wood or similar material, and the hollow post 6 on which the pressure member 8 is mounted to swing into various 20 positions over said bed. By vertically reciprocating said hollow post 6 as by means of an eccentric 9 on shaft 10, the pressure member 8 can be caused to approach the bed to exert pressure thereon. The handle 12 which is grasped by the operator for swinging the member 8 to the desired position over the bed is suitably connected to a clutch mechanism which is adapted to operatively 25 connect shaft 10 and its driving pulley 14 so that by depressing said handle after the member 8 has been swung to the desired position over the bed the said member is moved to exert pressure at the place desired. 30 For adjusting the height of the pressure member 8, the connection 15 between the eccentric 9 and the hollow shaft 6 that supports that pressure member is made adjustable as by means of a rod 16 operated by a 35 hand wheel 17.

40 The construction, above described, illustrates one type of press to which this invention may be applied but which in itself forms no part of the subject-matter of the 45 present application, being covered by the prior application, Serial No. 338,014, filed October 8, 1906.

50 Suitably secured to pressure member 8 is a plate 20 on which a tool carrier 22 is mounted so as to slide longitudinally of said member 8. On carrier 22 is mounted a block 24 which preferably is pivotally attached thereto by a pin 25 and which carries the 55 truing knife or tool 26 while a spring 27 mounted between said block and carrier tends to hold the tool 26 with its cutting edge in position to act upon the bed 4 of the machine, the limit of such movement being determined by contact of a part of block 24 60 with carrier 22. Journalized in the plate 20 is a screw 30 which passes through the carrier 22 for imparting thereto movement longitudinally of the member 8. Upon the end of this screw is a ratchet wheel 32 adapted 65 to be operated by a reversible pawl 33. This

pawl is seated in a recess formed in a pawl carrier 35 and is pressed toward the ratchet wheel 32 by a spring 36. The stem 37 of the pawl is provided with a head 38 upon which ribs 39 are formed that are adapted to engage recess 40 in the pawl carrier to maintain the pawl in one or the other of its adjusted positions. The pawl carrier 35 oscillates about the same axis of rotation as the screw 30 and is provided with two arms or extensions which extend into proximity to the opposite sides of an abutment 42 which in the construction illustrated in the drawing is in the form of a ball-headed bolt screwed into a socket 44 supported from a clamp 45 which is attached to the table 4 by a bolt 46.

70 In the construction illustrated in Fig. 5, the pawl carrier 35 in addition to the pawl 33 also carries a spring pressed plunger 48 seated in a second recess in said carrier and engaging the ratchet wheel 32 to prevent rotation thereof except when moved by pawl 33. The form of tool which is preferably used with this attachment is indicated in Fig. 6 and as shown said tool consists of a 75 bar cut out at the end to form a planing edge.

80 In the form of tool illustrated in Fig. 2 one edge only is adapted to serve as a planing edge but in that form illustrated in Fig. 4 the tool 28 is made double so that either 85 end may serve as the planing edge. The tool carrier 29 shown in this figure is supported somewhat differently from tool carrier 22 shown in Fig. 2, but in other respects the mounting of tool 28 is similar to that 90 shown in Fig. 2.

95 In the use of this apparatus the plate 20 is attached to the pressure member 8 and clamp 45 is attached to the table 4, preferably to one of the clamping strips 50 which are employed to hold together the wooden portion of the table. By turning abutment 100 42 in its socket the height of the portion thereof which acts upon pawl carrier 35 may be adjusted according to the height of the table 4 and socket 44 may also be adjusted 105 on its supporting clamp 45 to hold the said abutment at different distances from the bed. These adjustments are intended to bring the head of abutment 42 into position to coöperate properly with pawl carrier 35. Having adjusted pawl 33 to move the tool carrier 22 in the direction desired along the 110 pressure member 8, the operator grasps a handle 52 provided on plate 20 and swings the pressure member 8 over the table 4. The oscillations imparted by the operator to the pressure member 8 will bring the extensions 115 upon pawl carrier 35 into contact with opposite faces of abutment 42 so that the carrier will be rocked and will actuate the ratchet wheel 32. Thus by swinging the pressure member 8 over the table 4 the tool 26 or 120 125 28 will be forced 130

across the bed in contact with it and will act on successive portions of the bed on successive movements of said member 8 so as to true or smooth said bed as may be necessary.

5 A reversal of the direction of rotation of the ratchet wheel and consequently a reversal of the screw and of the direction of motion of the tool can be obtained by reversing the pawl in its mountings. The tool is 10 arranged to act upon the surface of the bed only when the pressure member 8 is being swung in one direction. On the return movement of pressure member 8 the block 24 which carries the tool turns about its 15 pivot 25 against spring 27 to permit the edge of said tool to slide over the surface of the bed.

As shown, the apparatus is provided with a safety device in the form of a bent arm 20 54 suitably attached to the plate 20 and extending under the handle 12 of the pressure member to prevent said handle from being depressed to cause reciprocation of said pressure member toward the bed 4 while the 25 attachment is in place. As shown in Fig. 7, the end of this handle 54 is forked to embrace the rod 55 which passes into a recess in said handle 12 and the ends of the forks are beveled to provide an adjustment for the 30 varying spaces found between the lower surface of the handle and the surface of the pressure member 8 in different machines. The provision of this curved arm 54 is important, for, as will be evident from an inspection of Fig. 1, if the press should be 35 started by a depression of handle 12 while the attachment is in place, the movement of pressure member 8 toward the bed 4 would probably cause breakage of the machine. As 40 shown also, the attachment is provided with a second safety device in the form of a spring pressed plunger 56 which bears against a flat surface formed upon the stem of the socket 44 which enables the abutment 45 42 to turn about the axis of the stem of the socket in case of abnormal stress being exerted upon the abutment either by reason of improper adjustment between said abutment and the pawl carrier 35, or by reason of the 50 pawl carrier 35 being prevented by any reason from oscillating. A bolt 58 is provided to adjust the degree of tension of the spring for the plunger 56. If desired, means, such as an adjusting screw 60, may 55 be mounted in tool carrier 22, this screw having a point which enters between block 24 and the side of said tool carrier 22 to turn said block on its pivot 25 against the force of spring 27, thereby raising the end 60 of tool 28 to an inoperative position in cases in which it is desired to keep the said tool temporarily out of action so that the traversing effect may be obtained without acting upon the bed. By this means, the 65 tool may be brought to any desired spot

over the bed before being moved to a position to act thereon.

Having described my invention, what I claim as new and desire to secure by Letters Patent of the United States is:

1. In a machine of the class described, the combination with a bed, of a pressure member movable over said bed into different operative relations thereto and movable relatively to said bed to exert pressure, and resurfacing means carried by said member and operating upon the coöperating surface of said bed to bring said surface into parallelism with the pressure surface of said member. 70

2. In a machine of the class described, the combination with a bed, of a pressure member laterally movable over said bed and a planing device removably mounted upon said member and arranged to act on the bed 85 to restore to parallelism the coöperating surfaces of said member and said bed. 80

3. In a machine of the class described, the combination with a bed, of a member angularly movable over said bed about a fixed 90 axis at one side of the bed, resurfacing means carried by said member and acting during the angular movements thereof to resurface the bed, and automatic means to cause said aforementioned means to act on 95 different portions of the bed. 90

4. In a machine of the class described, the combination with a bed, of a pressure member movable over said bed into different pressing relations thereto, resurfacing means 100 carried by said member for restoring to parallelism the coöperating surfaces of said member and said bed, and means to cause the resurfacing means to act on different portions of the bed during successive movements of said member over said bed. 105

5. In a machine of the class described, the combination with a bed, of a member angularly movable over said bed about a fixed axis at one side thereof, resurfacing means 110 carried by said member and acting during the angular movements thereof to resurface the bed, and automatic means to cause said resurfacing means to act on different and adjacent portions of the bed during successive angular movements of said member. 115

6. In a machine of the class described, the combination with a bed, of a pressure member movable over said bed into different operative relations thereto and movable relatively to said bed to exert pressure, resurfacing means carried by said member for restoring to parallelism the coöperating surfaces of said member and said bed, and reversible means acting automatically to 125 cause said resurfacing means to act on different portions of the bed during successive movements of said member over said bed. 120

7. A dying-out press, having in combination, a bed, a pressure member laterally 130

movable over said bed into different operative relations thereto and movable relatively to said bed to exert pressure, and resurfacing means carried by said member for bringing the surface of said bed into parallelism with the path of movement of said member.

8. A dying-out press, having in combination, a bed, a pressure member movable over said bed into different operative relations thereto and movable toward and away from the bed to effect a pressing operation, and resurfacing means removably mounted upon said member and operating during the movement of the pressure member over the bed for bringing the surface of said bed into parallelism with the path of movement of said member.

9. A dying-out press, having in combination, a bed, a pressure member movable thereover, and resurfacing means acting on the surface of said bed when in position in the machine for bringing said surface into parallelism with the path of movement of said member.

10. A dying-out press, having in combination, a bed, a pressure member movable over said bed into different operative relations thereto and movable toward and away from the bed to effect a pressing operation, a resurfacing tool carried by said member for acting on said bed, means for causing said tool to act on different portions of the bed during successive movements of said member over the bed, and means for adjusting said aforementioned means to correspond to changes in the height of the bed.

11. A dying-out press, having in combination, a bed, a pressure member movable over said bed into different operative relations thereto and movable toward and away from the bed to effect a pressing operation, a resurfacing tool carried by said member for acting on said bed, means for causing said tool to act upon different portions of the bed during successive movements of the pressure member over the bed and means for adjusting said aforementioned means to correspond to beds of different lateral areas.

12. In a machine of the class described, the combination with a bed, of a member movable thereover, a resurfacing tool carried by said member and arranged to act upon said bed, means for causing said tool to act upon different portions of the bed on successive actuations of said member, said means including a part which is arranged to yield in case of unusual resistance to the movement of said member.

13. In a machine of the class described, the combination with a bed, of a pressure member movable transversely into different operative relations thereto, mechanism for moving said pressure member toward and away from the bed to effect a pressing opera-

tion, a part fitted to be grasped by the operator for positioning said member over the bed, actuating connections between said part and said mechanism, removable resurfacing mechanism upon said member and an attachment carried by said member as it moves over the bed for preventing the actuation of said mechanism while said resurfacing mechanism is carried by said member.

14. In a machine of the class described, the combination with a bed, of a member movable transversely into different operative relations thereto, means for moving said member relatively to said bed to exert pressure, a handle arranged to be depressed to actuate said means, removable resurfacing mechanism on said member, and an attachment adapted to prevent the depression of said handle while said resurfacing mechanism is carried by said member.

15. In a machine of the class described, the combination with a bed, of a member movable transversely into different operative relations thereto, means for moving said member relatively to said bed to exert pressure, a handle arranged to be depressed to actuate said means, removable resurfacing mechanism on said member, and an attachment adapted to prevent the depression of said handle while said resurfacing mechanism is carried by said member, said attachment being adjustable to suit different heights of handle.

16. In a machine of the class described, the combination with a bed, of a pressure member movable over said bed into different pressing relations thereto, a resurfacing tool carried by said pressure member and having operative movement in one direction and a movement of adjustment in a direction at an angle to the direction of the operative movement, one of said movements taking place with the movement of the pressure member and the other of said movements being relative to said member.

17. In a machine of the class described, the combination with a bed, of a pressure member arranged to swing about a center at one side of the bed into different operative relations to the bed, a resurfacing tool carried by said pressure member and having operative movement in the arc of a circle and a movement of adjustment at an angle to said arc, one of said movements taking place with the movement of the pressure member and the other of said movements being relative to the pressure member.

18. In a machine of the class described, the combination with a bed, of a member arranged to swing about a center at one side of said bed into different operative relations to the bed, a resurfacing tool carried by said member and having operative movement with said member as it swings over the bed and movement of adjustment

along the radius of its arc of operative movement whereby successive operative movements may be in concentric arcs.

19. In a machine of the class described, 5 the combination with a bed and a pressure member, movable over the bed into different pressing relations thereto and movable toward and away from the bed to effect a pressing operation, of means for resurfac- 10 ing said bed to bring its pressure receiving surface into parallelism with the pressure

applying surface of said member, said means being constructed and arranged to be carried by said pressure member and having operative movement therewith over the bed. 15

In testimony whereof I have signed my name to this specification in the presence of two subscribing witnesses.
